HANGER, FOR PICTURES, MIRRORS, PLAQUES, OR THE LIKE

L. Richard Chasen, Port Chester, N.Y., assignor to Coats & Clark, Inc., New York, N.Y.

Filed June 11, 1971, Ser. No. 152,481

Term of patent 14 years

Int. Cl. D8—08

U.S. Cl. D8—257

FIG. 1.

FIG. 2.

FIG. 3.

FIG. 4.

FIG. 1 is a front view of the hanger, for pictures, mirrors, plaques, or the like;

FIG. 2 is a side view of the hanger;

FIG. 3 is a top view of the hanger; and

FIG. 4 is a bottom view of the hanger.

The side opposite FIG. 1 is similar in appearance.

I claim:

The ornamental design for a hanger, for pictures, mirrors, plaques, or the like, as shown and described.
